WATER SPRAYER

Miroslav Sigmund, Gosforth, England

Application November 26, 1947, Serial No. 788,137
In Great Britain November 12, 1945Section 1, Public Law 690, August 8, 1946
Patent expires November 12, 1965

5 Claims. (Cl. 299—68)

1

The present invention relates to improvements in water sprayers of the type comprising a nozzle usually rotatable, and a water diffusing or atomising element rotatably mounted on the nozzle so that the periphery thereof projects into the path of the water jet from the nozzle, rotation of the diffusing element and if necessary also the nozzle, being effected by reaction pressure of the water jet emerging from the nozzle, and the extent to which the said diffuser or atomiser element projects into the path of the water jet being variable.

In accordance with the invention a water sprayer is provided comprising a jet nozzle and a rotary diffusing element for the jet, said diffusing element being arranged to rotate in a plane of rotation intersecting the path of the jet about the axis of a supporting member itself movable relative to the jet nozzle under the reaction pressure between the jet and the diffusing element to move the axis of rotation of the diffusing element and thereby vary the extent of the projection of the diffusing element into the path of the jet.

Where, as is usually the case, the jet nozzle is also required to rotate about a vertical axis, the movable supporting member for the diffusing element may take the form of a shaft having the diffusing element fixedly mounted thereon and itself rotatable in a bearing connected with the jet nozzle and constructed to permit movement of the shaft towards and away from the nozzle, the said shaft being utilised in conjunction with suitable reduction gearing to impart rotation to the jet nozzle.

The invention is illustrated by way of example in the accompanying drawings in which

Fig. 1 is a view in side elevation of a complete sprayer;

Fig. 2 is a view in section on the line 2—2 of Fig. 1, and on a larger scale, of the gearing utilised to rotate the jet nozzle;

Fig. 3 is an end view partly in section and on a larger scale looking towards the end of the nozzle in the direction of the arrow in Fig. 1; and

Fig. 4 is a sectional view of the jet nozzle taken on the line 4—4 of Fig. 1.

Referring to the drawings, the jet nozzle is formed by a tubular barrel 1 having a suitable jet aperture 2 at one end and fixedly connected at the other end to a curved hollow body 3.

The curved hollow body 3 is fixedly connected with an inner tubular extension 4 which is a rotating fit within a sleeve 5 supported by a collar 6 in a tripod 7, the lower end of the tubular ex-

2

tension 4 engaging a shoulder 8 within sleeve 5. The sleeve 5 is provided at its lower end with a junction piece 9 for connection with a water supply pipe (not shown).

At the upper end of the sleeve 5 is fixedly mounted a ring 10 within which the tubular extension 4 can rotate, the ring 10 being provided with a radially outwardly directed flange 11. Packing rings 12 are provided between the sleeve 10 and the tubular extension 4 to provide a watertight joint.

The curved hollow body 3 at its lower end is surrounded by an integrally formed curved section flange 13 which covers the radial flange 11 on ring 10, and the space within the flange 13 is closed from below by a ring 14 between which and the lower side of radial flange 11 is mounted an anti-friction thrust bearing 15. The outer periphery of radial flange 11 is toothed to form a worm gear wheel.

When the sprayer is mounted, as shown in Fig. 1, the barrel 1 extends at an upward inclination and is adapted to rotate on the bearing 15 about the vertically disposed axis of sleeve 5.

The barrel 1 at the outlet end is preferably filled with a nest of parallel tubes 16, Figs. 1 and 4, to eliminate or reduce turbulence.

The diffuser is in the form of a spoked wheel 17 having a plurality of uniformly inclined vanes 18 formed on its periphery. As an example the vanes are inclined at an angle of about 45° to the plane of the wheel and may be of uniform angular width and spacing with the exception of two or more vanes 18' equally distributed

around the periphery; which are of approximately twice the angular width and radial length of the others. The circumferential spacing between adjacent vanes 18 may be a small fraction e. g. one fifth the angular width of the small vanes, the spacing between a large vane 18' and adjacent small vanes however being somewhat greater.

The diffuser or vane wheel 17 is fixedly mounted on the end of a shaft 19 extending alongside the nozzle 1 and rotatably supported in bearings connected with the nozzle, the plane of rotation of the vane wheel or diffuser 17 extending in a general direction normal to the axis of the nozzle and with the peripheral vanes 18 and 18' thereof arranged to project into the path of a water jet emerging from the nozzle.

The wheel 17 is preferably braced by means of a spider the arms 20 of which radiate from an extension of the wheel hub.

The bearing for the forward end of the shaft

19 is formed by a bush 21 which is carried in trunnion bearings 22 between the extremities of a pair of arms 23 rigid with, and extending outwards from, a yoke 24. The ends of the yoke are mounted on pivots 25 provided on diametrically opposite sides of the barrel 1 and axially aligned with one another so that the yoke may swing towards and away from the barrel 1. The axes of the trunnion bearings 22 and of the pivots 25 in the case illustrated lie in or near a common plane. A flange 26 serves to limit the longitudinal movement of the shaft 19 in the bush 21 in the outward direction i. e. to the right in Fig. 1.

The other end of the shaft is provided with a sliding coupling formed by a pin 27 on the main part of the shaft sliding in longitudinal slots 28 in a sleeve extension 29, and the sleeve extension is connected through a flexible joint 30 with the spindle 31 of a gear worm 32 mounted in bearings in a casing 33 fixed to the flange 13 on curved hollow part 3.

The worm 32 (Fig. 2) meshes with a worm wheel 34 fast on a spindle 35 driving a further worm 36 which meshes with the teeth on the periphery of the radial flange 11 on ring 10 fixed at the upper end of stationary sleeve 5.

When the sprayer is set in operation the water jet from outlet 2 impinges upon the inclined vanes 18, 18' of the vane wheel 17 the direction of impact being such as to deflect the water upwards. The wheel 17 is thus set into rotation together with the shaft 19 on which the wheel is fixed, so that drive is imparted to the gearing 32, 34, 36 and the barrel or jet nozzle is rotated about the vertical axis of the stationary toothed flange 11. Pressure of the jet on the vanes of the wheel 17 during speeding up causes the rotating shaft 19 to move, first a small distance longitudinally along the barrel 1, as is permitted by the sliding coupling 27, 28, 29, to bring the flange 26 fast on the shaft 19 into engagement with the end of the bush 21, and thereafter the yoke 24 and the integral arms 23 carrying the bush 21 are rocked about the pivots 25 so that the bush 21 is moved outwards from a position close to the barrel 1 as shown in dotted lines in Fig. 3, to a position such as that shown in Fig. 1 or in full lines in Fig. 3, the bush turning in its trunnion bearings 22, so that the forward end of the shaft 19 takes a position further from the axis of the barrel as clearly shown in Fig. 3.

The vanes of the diffuser 17 are thus caused to withdraw at least partially from the path of the water jet as shown in Fig. 3 so that the water impinges upon the edges or peripheries of the small vanes 18 instead of in the region of the centres thereof while still meeting the large vanes 18' near their centres.

Under these running conditions continued rotation of the vaned wheel 17 with shaft 19, and therefore also of the jet nozzle about the vertical axis, is effected at least for the main part by impact of the jet on the larger vanes 18'. Movement of the shaft 19 and the diffuser 17 in the reverse direction to that described above, i. e. when returning to rest after use, or upon reduction of the water pressure, is effected in the case illustrated by gravity.

In use the water is distributed by the diffuser 17 in the approximate form of a flat curtain closely simulating rain, the curtain moving slowly about the vertical axis of rotation of the jet nozzle.

Water striking the large vanes 18' falls to the

ground in such manner as to form approximately the half of the curtain nearest to the sprayer whilst the more distant half or part of the curtain is formed by water which has been deflected by the smaller vanes 18.

As an example, with a water pressure of about 60 lbs. per square inch the diffuser will rotate with a speed in the region of 3500 revs. per minute, the jet nozzle making one complete turn in about 1½ minutes.

The length of the curtain can, within limits, be maintained approximately constant with different water pressures by varying the area of the jet orifice e. g. by substituting one nozzle end for another.

I claim:

1. A water sprayer comprising a jet nozzle adapted to project a water jet at an upward inclination when in use, a rotary diffusing element 20 adapted to rotate in a plane intersecting the path of the water jet from said nozzle so as to break up the water jet, a shaft carrying said rotary diffusing element and rotatable therewith, a bearing for said shaft including a sleeve itself 25 mounted to rock in a plane substantially parallel with the jet nozzle, a carrying member for said sleeve pivoted on the jet nozzle for movement of the sleeve carried by said carrying member towards and away from the jet nozzle, and a flange 30 on the shaft adapted to engage and move the sleeve in the direction away from the jet nozzle by an endwise movement of the shaft imparted thereto by pressure of the water jet on the diffusing element.
2. A water sprayer comprising a jet nozzle, adapted to project a water jet at an upward inclination when in use, a rotary diffusing element adapted to rotate in a plane intersecting the path of the water jet from said jet nozzle 35 so as to break up the water jet, said rotary diffusing element being also adapted for movement of limited extent in the direction of its axis of rotation, a shaft extending alongside and longitudinally of the jet nozzle said shaft carrying 40 said rotary diffusing element and being rotatable therewith, a bearing for said shaft, a carrying member for said bearing freely pivoted on said jet nozzle to swing said bearing towards and away from and longitudinally of said jet 45 nozzle and in a plane substantially parallel with said jet nozzle, said pivoted carrying member being movable in one direction about its pivot by movement of the rotary diffusing element in the direction of the axis of the said shaft, by 50 pressure of the water jet on said diffusing element.
3. A water sprayer comprising a jet nozzle adapted to project a water jet at an upward inclination when in use, a rotary diffusing element 55 60 adapted to rotate in a plane intersecting the path of the water jet from said jet nozzle under reaction pressure of the water jet, and thus acting to break up the water jet, said rotary diffusing element being also adapted for movement of limited extent in the direction of its axis of rotation, an axis shaft for said diffusing element, means supporting said axis shaft parallel to the general direction of the axis of said jet nozzle, said supporting means including a bearing member 65 for said axis shaft and a carrying member for said bearing member located near the end of said axis shaft adjacent said diffusing element and freely pivoted for swinging movement on said jet nozzle to move said bearing member in a 70 plane substantially parallel with the jet nozzle, 75

and an abutment on said axis shaft adapted to transmit axial movements of said diffusing element and its axis shaft to said bearing member and said carrying member to effect swinging movements thereof in said plane and movement of the axis shaft towards and away from said jet nozzle, thereby varying the extent of the projection of said diffusing element into the path of the jet.

4. A water sprayer comprising a base support, a jet nozzle mounted for rotation about a fixed axis on said base support and adapted to project a water jet at an upward inclination when in use, a rotary diffusing element adapted to rotate in a plane intersecting the path of the water jet from said jet nozzle under reaction pressure of the water jet, and thus acting to break up the water jet, said rotary diffusing element being also adapted for movement of limited extent in the direction of its axis of rotation, and axis shaft carrying said diffusing element and rotatable by and with said diffusing element, means supporting said axis shaft parallel to the general direction of the axis of said jet nozzle, said supporting means including a bearing member for said axis shaft and a carrying member for said bearing member located near the end of said axis shaft adjacent said diffusing element and freely pivoted for swinging movement on said jet nozzle to move said bearing member in a plane substantially parallel with the jet nozzle, an abutment on said axis shaft adapted to transmit axial movements of said diffusing element and its axis shaft to said bearing member and said carrying member to effect swinging movements thereof and movement of the axis shaft in said plane towards and away from said jet nozzle, thereby varying the extent of the projection of said diffusing element into the path of the jet, gearing between said axis shaft and said rotatable jet nozzle and a sliding coupling between said axis shaft and said gearing whereby said gearing may be driven by said axis shaft and said jet nozzle rotated on said base support.

5. A water sprayer comprising a base support, a jet nozzle mounted for rotation about a fixed axis on said base support and adapted to project a water jet at an upward inclination when in

use, a rotary diffusing element adapted to rotate in a plane intersecting the path of the water jet from said jet nozzle under reaction pressure of the water jet, and thus acting to break up the water jet, said rotary diffusing element being also adapted for movement of limited extent in the direction of its axis for rotation, an axis shaft carrying said diffusing element and rotatable by and with said diffusing element, means supporting said axis shaft parallel to the general direction of the axis of said jet nozzle, said supporting means including a bearing member for said axis shaft and a carrying member for said bearing member located near the end of said axis shaft adjacent said diffusing element and freely pivoted for swinging movement on said jet nozzle about an axis in a substantially vertical plane containing the axis of the jet nozzle, and approximately normal to the axis of the jet nozzle, to move said bearing member in a plane substantially parallel with the jet nozzle, and an abutment on said axis shaft adapted to transmit axial movements of said diffusing element and its axis shaft to said bearing member and said carrying member to effect swinging movements thereof in said plane approximately parallel with the jet nozzle, and movement of the axis shaft towards and away from said jet nozzle, thereby varying the extent of the projection of said diffusing element into the path of the jet.
